JAY WHEELOCK, OF SAN FRANCISCO, CALIFORNIA.

Letters Patent No. 96,521, dated November 2, 1869.

IMPROVED BALE-TIE LOCK.

The Schedule referred to in these Letters Patent and making part of the same.

Be it known, to whom these presents shall come, that I, JAY WHEELOCK, of the city and county of San Francisco, State of California, have made a new and useful Improvement in Bale-Tie Locks, of which the following is a description, which, taken together with the drawings, figures, and letters thereon, will enable any one skilled in the art to make and use the same.

The band is made of ordinary strap-iron of suitable length and size, bent over at one end, A, from a half inch to any desired length, so as to admit of receiving a double lap, that is formed at the other end, B, of the band, and is made by first making a bend of sufficient length to allow the end enough room to be turned up when the slide is on; then make another bend of a half inch, or any desired length, on the doubled end. This, when hooked together, forms the tie, and is ready for the slide-lock M, which is of metal, and formed with bevelled edges, K K, to slide easily over the laps A and B of the tie after they are united.

The lock M is also formed with a flange, L, which partially closes one end of the slide or lock.

When the slide is passed over the lap, the double

lap and hook fill up the inside of the lock M, so that when it meets the flange L, it locks the slide from passing over the lap. The end of the double lap B is now turned up, and prevents the slide from slipping back, thus forming a double lock while in use.

It will be seen that this lock-tie does not destroy either the band or the lock, as it will be easy to straighten the end, and it is again ready for use.

Figure 1, lock and tie, sectional view.

I do not claim, as my invention, bands or locks covered by slides, for these I know to be old; but

What I do claim, and desire to secure by Letters Patent, is—

The bale-tie lock, composed of the slide M, with its interior flange or shoulder L, in combination with the band or strap having the folded end A, and double-lapped and curved end B, when said parts are constructed, arranged, and applied together, in the manner and for the purpose herein shown and described.

JAY WHEELOCK.
